UNITED STATES PATENT OFFICE.

HARRY H. LABADIE, BURTON B. BEERS, AND WILLIAM O. STARK, OF CHICAGO, ILLINOIS, ASSIGNORS, BY DIRECT AND MESNE ASSIGNMENTS, OF ONE-HALF TO SAID LABADIE AND ONE-HALF TO THE ESTATE OF WILLIAM SCHWEITZER, DECEASED.

LUNCHEON-TABLE FOR AUTOMOBILES.

1,189,835.

Specification of Letters Patent. Patented July 4, 1916.

Application filed August 31, 1914. Serial No. 859,413.

To all whom it may concern:

Be it known that we, HARRY H. LABADIE, BURTON B. BEERS, and WILLIAM O. STARK, citizens of the United States, and residents 5 of the city of Chicago, in the county of Cook and State of Illinois, have invented certain new and useful Improvements in Luncheon-Tables for Automobiles; and we do hereby declare that the following description of our 10 said invention, taken in connection with the accompanying sheets of drawings, forms a full, clear, and exact specification, which will enable others skilled in the art to which it appertains to make and use the same.

15 This invention relates generally to improvements in a luncheon table for automobiles, and it consists, essentially, in the novel and peculiar combination of parts and details of construction, as hereinafter first 20 fully set forth and described and then pointed out in the claims.

In the drawings already referred to which serve to illustrate our said invention more fully, Figure 1 is a perspective view of our 25 joint invention. Fig. 2 is a front elevation thereof, and Fig. 3 a side elevation with certain parts shown in section. Fig. 4 is a partial section of a quick acting tensioning device employed. Fig. 5 is a front elevation 30 of Fig. 4, and Fig. 6 an enlarged elevation of the same with certain parts left out for sake of clearness of disclosure. Fig. 7 is a vertical section of a fragment of the supporting post incorporated in our invention, 35 and Fig. 8 is an elevation of a fragment thereof.

Like parts are indicated by corresponding characters or symbols of reference in all the figures of the drawing.

40 The essence of this invention resides in the production of a portable luncheon table for automobiles and the like which is wholly and entirely supported from the floor of the vehicle upon suitable standards, in which are 45 incorporated original tensioning means adapted to enforce any desired pressure of frictional contact of the said table against an adjacent seat back of such a vehicle, so as to prevent any independent vibration of said table while the vehicle is in motion. 50 And, correlated thereto, are original and novel quick acting devices for applying or releasing the tension aforesaid.

In the present practice of our invention

we employ as the table member proper, a 55 combined luncheon case and table forming the subject matter of an application for design patent of Harry H. Labadie, filed August 3, 1914, Serial No. 854,883, though it is to be understood that any desired form 60 or construction of table member may be used instead.

Referring now to the drawings, A indicates the table member proper in general. To the bottom wall 10 or equivalent thereof 65 are permanently affixed U-shaped lateral guides 11, having inturned outer flanges 11^a, forming guide-ways 12, Fig. 3, for the reception of supporting blades or bars 12^a. The outer ends of these supporting bars are 70 pivoted at 12^b to posts 13, which posts are disposed in a vertical plane for a portion of their length and then bent at an angle to the perpendicular at 14 as indicated in Figs. 1 and 3. At the inner end of the supporting 75 bars 12^a are provided depending lugs 15, to which are pivoted arcuate, downwardly extending, threaded, tension rods 16, the radius of which rods is determined from the pivotal points 12^b. Located in the supporting bars 80 12^a are thumb screws 17, whereby the table member A may be locked in position, and it is now to be understood that the guide-ways 12 are in slidable engagement with the supporting bars 12^a, so that when the thumb 85 screws 17 are released, the table member A may be easily disengaged from said supporting bars in a manner readily comprehended.

Drilled or otherwise punctured through 90 the posts 13 are openings 18, Fig. 3, through which the tension rods 16 are adapted to project, there being, in the cheapest development of this invention, thumb nuts 19, threaded over said rods and bearing against 95 the posts 13, whereby a tension may be created in said rods by rotating said nuts. The posts 13 are sustained in position by a base casting 20, having a pair of upstanding, parallel lugs 21, which are internally bored 100 for the free reception of said posts. One wall of each of these lugs 21 is slotted at its upper end and provided with clamping ears 22, which are adapted to be tightened by screws 23, thereby maintaining the posts 13 in placed position. Base casting 20 is provided with laterally extending floor flanges 105 24, alined with the lugs 21 to provide ample

footing for said base structure along the line of stress created by said tension rods. Bolts 100 secure said structure to the floor of a vehicle. Fixed to that portion of the table member A adjacent a seat back B of an automobile or other vehicle, are a plurality of rubber cushions or bumpers 25 which contact with the said seat back to increase the co-efficient of friction between the table member and the seat back.

The operation of our device may now be described as follows, reference being had to Fig. 3, in which the table member is expressed in the form of a convertible luncheon case. The said case is first engaged with the supporting bars 12^a as already described and the thumb nuts 19 are then rotated in the proper direction to enforce contact of the rubber bumpers 25 with the seat back B, by creating a tension in the rods 16. This enforced frictional contact will prevent any independent vibration of the table member in a manner easily comprehended.

In Figs. 4, 5, 6, 7, and 8 we disclose a quick acting device for creating and releasing the tension in the rods 16. With this device the apertures 30 through the posts 13 are formed with oppositely disposed spiral cam faces 31 and 31^a, and on the face of said posts surrounding the said opening 30 are produced helical cam faces 32 and 32^a. Freely fitting within the opening 30 are two mating semi-cylindrical sleeves 33 and 33^a provided at one end with helical cam faces 34 and 34^a adapted to co-act with the like cam faces 32 and 32^a surrounding the opening 30. Said sleeves are internally apertured, and at the end adjacent the cam faces 34 and 34^a are threaded for engagement with the threaded portion of the rods 16. These internal screw threads proceed only a short distance, and the remainder of apertures 35 are distinctly larger in diameter than the said rods, and it is now to be noted that when the said sleeves have their longitudinal edges in contact, there will be a free engagement only of the threads in said sleeves with the threads on the rods. On the periphery of the sleeves 33 and 33^a, diametrically opposite each other, are formed semi-circular longitudinal ridges 36 and 36^a which ridges engage the cam faces 31 and 31^a, whereby upon rotation of said sleeves in the proper direction, the said ridges co-acting with the said cam faces, tend to close the sleeves into engagement with the screw threaded rods. At the same time the cam faces 32 and 32^a and 34 and 34^a are co-acting to produce an endwise motion of the said sleeves and rods 16, so as to create a tension in the latter. For sake of clearness it is here explained that the diametrical distance between the ridges 36 and 36^a when the sleeves are solidly closed together is

slightly less than the diameter of the opening 30 at its least diameter, so that there is no excessive frictional resistance to the rotation of the sleeves. In the marginal walls of these sleeves are formed coinciding chambers for the reception of helical springs 40, which are provided to insure the spreading apart of the sleeves when the direction of rotation thereof is reversed. At the opposite end of the sleeves 33 and 33^a, are formed hinge ears 41 and 41^a, embracing which is a hub 42 of an actuating arm 43, pins 44 passing through said hub and said hinge ears being provided to maintain the parts in assembled relationship.

The sleeves 33 and 33^a exceed the length of the opening 30 in the posts 13 by the amount of endwise motion provided for by the cams 32 and 32^a and 34 and 34^a, plus the width of hub 42 and sufficient space for a spring 45, embracing said sleeves between the posts 13 and hub 42, when the same is compressed, the object of this spring being to return the sleeves to the position shown in Fig. 4 as the handle member 43 is rotated in reverse direction. It will now be seen that while the sleeves are in the position indicated in Fig. 4, the ridges 36 and 36^a are located in opening 30 at the point of its largest diameter, and the sleeves, therefore, are spread apart due to the action of springs 40, thereby permitting free movement of the rods 16 backward and forward through said sleeves.

When applying the table member to the supporting bars 12^a, the latter are first raised as far as possible, and the sleeves 33 and 33^a rotated to clamp the rods 16 so as to maintain said bars in their raised position. The guide-ways 12 are then slipped over said supporting bars and the thumb screws 17 tightened, after which the sleeves are reversely rotated, releasing the rods 16 and permitting the bars 12^a and the attached table member A to drop by gravity until the bumpers 25 contact with the seat back B. The sleeves are now again rotated, creating a tension in the aforesaid rods 16 to enforce frictional contact with said seat back, to maintain the table member against independent vibration.

Attention is now directed to the fact that the rods 16 need not be round threaded rods. Flat punched sheet metallic arcuate strips with a plurality of serrations along the edges thereof will serve the same purpose, but the round rods are preferred because of lesser cost of production.

It is now explained that the distance from outside to outside of hinge ears 41 and 41^a when the sleeves are closed together and before the hub 42 is applied is slightly less than the greatest diameter of opening 30, so that in assembling these parts the said sleeves are manually squeezed together and

introduced into said opening with the ears 41 and 41^a at the point of greatest diameter thereof.

While herein we have disclosed the preferred mode of practising our invention, we desire it understood that we may make such changes and alterations therein as might suggest themselves to one skilled in the art or permitted under the doctrine of equivalents.

Having thus fully disclosed our invention we claim as new and desire to secure to ourselves by Letters Patent of the United States:—

15 1. A supporting structure for automobile tables and the like including, in combination, an uprightly sustained post having a table supporting bar pivoted thereto, there being a chamber through said post possessed 20 of spiral cam faces, internally apertured members coacting with said cam faces in said chamber adapted for diametrical and longitudinal movement therein upon rotation thereof, and a tension member in connection with said bar, engaged by said apertured members.

2. A supporting structure for automobile tables and the like including, in combination, an uprightly sustained post having a 30 table supporting bar pivoted thereto, there being a chamber through said post, helical cam faces on said post surrounding said chamber, internally apertured members in said chamber engaging said cam faces and 35 adapted for diametrical and longitudinal movement therein upon rotation thereof, and a tension member in connection with said bar, engaged by said apertured members.

3. In combination, a base structure, an 40 uprightly sustained post therein, having an opening therethrough possessed of spiral cam faces, and helical cam faces on said post surrounding said opening, internally apertured members in said opening coacting with 45 said spiral and said helical cam faces, means for rotating said members, a supporting bar in pivotal relationship with said post, and a tension member connected to said supporting bar and engaged by said internally apertured members.

4. In a device of the class described, including a seat and a floor of an automobile and the like, a support mounted on said floor in adjacency to the back of the said

seat, posts arising from said support and 55 having their upper portions bent obliquely back, and a table member having its substantially rear edge in pivotal connection with the upper ends of said posts, said table member being adapted to be swung from a 60 substantially horizontal position up and beyond the perpendicular plane of said pivotal connection, whereby said table member will be maintained in an upright position against the back of said seat by gravity.

5. In a device of the class described, including a seat and a floor of an automobile and the like, a base structure located on said floor in adjacency to the rear of said seat, said base having an upstanding socket at 70 either end thereof, posts having vertical portions fitted in each of said sockets, each of said posts being possessed of an oblique and upwardly bent portion extending rearwardly beyond said base, and a table member pivotally connected to the upper ends of said oblique portions along its substantially rear edge thereof, whereby the front face of said table member will contact the rear face of said seat by the force of gravity. 80

6. In a device of the class described, the combination with a frame and a seat arising therefrom, of a support arranged in the rear of the seat and having a transverse base mounted on the frame, a rod extending vertically up from said base with its upper portion bent obliquely back, a table pivoted to the upper extremity of the rod, said pivot being located in the rear of the longitudinal center of the surface to which it is attached; 85 said rod being provided with a transverse opening in the vicinity of its bend, and an arcuate bar pivoted at its upper end to the table at a point in front of the pivoting point of the rod and having its lower portion slidably fitting through the transverse opening in the rod, and means for fixing 90 said rod in unslidable position.

In testimony whereof we have hereunto set our hands in the presence of two sub- 100 scribing witnesses.
